INCENDIARY BOMB

Paul N. Gillon, Alexandria, Va.

Application March 13, 1945, Serial No. 582,471

4 Claims. (Cl. 102—6)

(Granted under the act of March 3, 1883, as
amended April 30, 1928; 370 O. G. 757)

1

The invention described herein may be manufactured and used by or for the Government for governmental purposes without the payment to me of any royalty thereon.

This invention relates to incendiary bombs, and more particularly to a bomb adapted to lay down a pattern of incendiary elements substantially concentric with the point of impact of a demolition bomb.

A main object of this invention is to provide an incendiary bomb having desired ballistic characteristics so that a close approximation of a concentric incendiary pattern may be obtained with respect to a demolition bomb dropped immediately preceding the incendiary bomb.

A further object of this invention is to provide a main incendiary bomb containing clusters of small incendiary bombs, said main incendiary bomb being adapted to disintegrate at an optimum distance above the target and to disperse the small incendiary bombs to provide maximum effectiveness of said small incendiary bombs as they land around the point of explosion of the demolition bomb.

Further objects of the invention will become apparent from the following description and claims, and from the accompanying drawings, wherein:

Figure 1 is a longitudinal cross-sectional view of an incendiary bomb in accordance with this invention.

Figure 2 is an enlarged cross-sectional view taken on line 2—2 of Figure 1.

In the prior art, the dropping of the demolition bomb is followed at a definite time interval by a cluster of incendiaries with the hope that the center of impact of the incendiary cluster will be substantially coincident with the point of impact of the demolition bomb and further that the dispersion of the cluster will result in a reasonably satisfactory incendiary pattern. From the high altitudes from which the bombs are dropped, it is almost futile to hope that these objectives will be achieved since the disintegration of the cluster plus the very random ballistic characteristics of the incendiary bombs themselves result in a heterogeneous flight pattern wholly subject to the many sources of deviation inherent in the varying meteorological conditions which may exist at the time and place at which the bombs are dropped, and the unpredictable effect thereof on small incendiary missiles which are inherently very inefficient ballistically.

Incendiary bombs, as their name implies, are used to spread destruction by fire, and are gen-

2

erally used in association with demolition bombs. The destructive effect of the demolition bomb upon impact is produced by the violence of the detonation. The incendiary bombs, small and hexagonal in shape, are arranged in clusters and dropped from the plane as a unit, coming apart in the air to arm and fall separately to cover the area of destruction of the demolition bomb and complete by fire the destruction originated by the said bomb. There is, of course, tactical necessity of obtaining an incendiary pattern concentric with the point of impact of the demolition bomb if the incendiary is to be effective in carrying out this function.

15 The incendiary clusters thrown from the plane were not stable, and did not have, or even approach the ballistic efficiency of the demolition bomb. There was no way of adjusting the pattern, and the bombing plane had not only to remain over the target, but was often required to repeat the run on a lower level at a greatly increased hazard, due to the usual increase in anti-aircraft fire after the dropping of demolition bombs, in order to obtain even a minimum concentration of the incendiaries. This old method was not susceptible of material improvement even with this added effort and risk. I felt that if the cluster was encased in a shell or body to form a bomb which might be dropped from the plane in the same manner as the demolition bomb, and which would permit use of ballistic coefficients and aiming sights, the exact time lag required between the dropping of the two bombs might be readily determined and a reasonable approximation of the concentric pattern obtained, so that the center of impact of the incendiary cluster would be sensibly coincident with the point of contact of the demolition bomb.

20 It is a prime purpose of this invention to achieve the desired objectives by housing the incendiary bombs in a sheath or body of relatively brittle material, such as plastic or the like, and in such a manner that ballistic characteristics differing only slightly and in a known manner from those 25 of the demolition bomb with which the incendiary bombs are to be dropped are obtained.

25 By dropping the incendiaries housed as above described after a predetermined time lag with respect to the dropping of the demolition bomb, 30 by providing means for disintegrating the sheath or body at an optimum distance above the target, a very reasonable approximation of the desired concentric pattern may be achieved. The optimum distance selected may be such that explosion of the demolition bomb will have subsided

sufficiently to permit the maximum effectiveness of the incendiary bombs which subsequently land around the point of explosion of the demolition bomb.

Referring now to the drawings, the numeral 1 designates generally an incendiary bomb of my invention, comprising a sheath or housing 1a for the cluster of small inter-locking incendiary bombs 2 combined in a compact group tightly bound together by frangible band elements 3. Housing 1a may be made of plastic or other relatively brittle material adapted to be readily disintegrated. The nose portion 13 of housing 1a is provided with a fuze 4 of a type adapted to be set for explosion at a predetermined altitude above the ground.

A rearwardly tapered metal tail section 10 supporting a tail fin assembly 11, to complete the bomb and stabilize its flight, is secured to said housing 1a in any suitable manner, such as riveting, as at 12. Suspension lugs 14 for use in Army bomb racks, or a single suspension lug 15 for similar Navy use, or both, are secured to housing 1a by riveting or otherwise. The group of incendiary bombs 2 are secured within the housing 1a by pressure of the walls of said housing, as shown in Figure 2, and are restrained from longitudinal translative movement relative to the said housing by the tapered nose and tail portions 13 and 10, respectively.

The numeral 5 designates a metallic burster tube disposed axially in the housing 1a within the group of small incendiary bombs 2 containing an explosive charge 6 of any suitable explosive, which upon ignition and explosion will cause the tube 5 to expand and push out the bombs 2 after shattering of the housing 1a and the frangible bands 3 by the pressure set up within the said tube. A collar 7 is provided for securing the forward end of said tube 5 to the fuze 4 to form a continuous flame passage through which the flame from the burning primer within the said fuze may communicate with the explosive 6 to explode it. The rear end of tube 5 is supported in a socket 8 in a base plug 9 of the tail portion 10. The said tube 5 also cooperates with the housing 1a in supporting the group of small bombs within the said housing.

The ballistic characteristic of the assembled incendiary bomb are thus brought close to those of demolition bomb, and being known in relation to the ballistic characteristics of a demolition bomb, said incendiary bomb may be dropped at an accurately timed interval after dropping the demolition bomb so that the incendiary pattern will be concentric with the point of explosion of the demolition bomb.

Fuse 4 is preset for explosion at a predetermined height above the ground, said height being sufficient to secure proper dispersion of the small incendiary bombs resulting from the explosion of fuse 4 to provide a satisfactory incendiary pattern around the point of explosion of the demolition bomb. The fuze is not limited to any particular type, but may be a time fuze, a barometric pressure fuze, a proximity fuze, or any other fuze adapted to be set to function at a predetermined elevation relative to the earth, as occasion may demand. The fuse has its nonexplosive functioning elements external to the bomb body and the fuse itself is connected to the bomb body in the conventional manner. This fuse should be mounted so that its detonator or squib will flash through the continuous central channel of the burster tube 5 containing the ex-

plosive which is adjusted so that the resulting explosion will cause the said tube to expand under the pressure built up by said explosion rupture the sheath and disintegrate the clustered incendiaries. The force of the explosive pressure built up within the tube 5 is not only sufficient to disintegrate housing 1 but will also break frangible bands 3 scattering the small incendiary bombs 2. The force of this explosion, however, is not great enough to break up or to immediately ignite the small incendiary bombs, such ignition occurring when the small incendiary bombs land. At the time of dispersion, the incendiary bombs will be close enough to the ground so that their erratic flight characteristics will not substantially deflect the incendiary pattern away from satisfactory concentric relation to the point of explosion of the demolition bomb.

Since the whole objective of the invention is to correct the ballistic inefficiencies of incendiary bombs as compared with demolition bombs, I have herein disclosed an incendiary bomb whereby the objective desired is achieved by nesting the small incendiary bombs in a shaped plastic body in such a manner that the center of gravity, longitudinal and transverse moments of inertia, and the slenderness ratio of the incendiary missile produces a ballistic coefficient only slightly inferior to that of the demolition bomb with which it is intended to be used.

As heretofore pointed out, the disintegrating charge can be made up of any explosive especially fitted for use in a particular bomb, and in such readily determinable amount as would provide the disintegrating force necessary to accomplish the proper distribution of the incendiary cluster without breaking up any individual small bomb. While a specific embodiment of an incendiary bomb has been disclosed in the foregoing description, it will be understood that various modifications within the spirit of the invention may occur to those skilled in the art. Therefore, it is intended that no limitations be placed on the invention except as defined by the scope of the appended claims.

What is claimed is:

1. An incendiary bomb adapted to be released from aircraft, comprising a streamlined brittle body, a cluster of small incendiary elements nested within said body, frangible means binding said elements together to form said cluster, explosive means positioned within said cluster adapted to rupture said body and said frangible means simultaneously to scatter said incendiary elements, and a fuze carried by said body adapted to function at a predetermined distance above the ground to explode said explosive means.

2. An incendiary bomb adapted for release from aircraft, comprising an elongated brittle body provided with a tapered nose portion, a separate rearwardly tapered tail portion attached thereto, the said tail portion being adapted to provide flight stability, a plurality of incendiary elements positioned within said body, the said elements being securely bound together to form a compact cluster by a plurality of frangible bands and restrained from longitudinal movement within the said body by the nose and tail portions thereof, a burster tube containing an explosive mounted within said cluster to rupture said housing and said frangible bands, a fuze adapted to be set to function at a predetermined altitude above the ground mounted in the nose portion of said body and communicating with said explosive to explode the same, and means

carried by said body for releasably suspending said bomb in an airplane, whereby the ballistic characteristics of said bomb may be determined with reasonable accuracy.

3. An aerial bomb for dispensing a plurality of incendiary bombs dropped from an airplane at an optimum distance above a target, comprising in combination a tapered plastic body having a tail portion, including fixed fins, to house a plurality of incendiary bombs therein, frangible means securing said bombs together for positioning in said body, a fuze adapted to be set to function at a definite point above the earth carried by said body, and explosive means within said body adapted to be exploded by said fuze, whereby the said body and said frangible means are ruptured to dispense said incendiary bombs.

4. The structure of claim 3 in which means are carried by said bomb for releasably securing said bomb in the bomb rack of an airplane.
